UNITED STATES PATENT OFFICE.

WILLIAM T. MOORE, OF RICHVIEW, ASSIGNOR OF ONE-HALF TO W. HENRY MOORE, OF NASHVILLE, ILLINOIS.

COMBINED SACK-HOLDER AND SCALE.

SPECIFICATION forming part of Letters Patent No. 270,094, dated January 2, 1883.

Application filed October 17, 1882. (No model.)

To all whom it may concern:

Be it known that I, WILLIAM T. MOORE, a citizen of the United States, and a resident of Richview, in the county of Washington and State of Illinois, have invented a new and valuable Improvement in Combined Sack-Holders and Scales; and I do hereby declare that the following is a full, clear, and exact description of the construction and operation of the same, reference being had to the annexed drawings, making a part of this specification, and to the letters and figures of reference marked thereon.

Figure 1 of the drawings is a representation of this invention in a perspective view. Fig. 2 is a detail in perspective, and shows the spreaders with their holding branches and teeth.

This invention has relation to weighing devices for the use of grocers and others in filling paper sacks with grain, sugar, flour, and other articles; and it consists in the construction and novel arrangement of the base, fulcrum-post, and balance-beam pivoted thereto, the suspended receiver and spring-scale, the adjustable chain connecting the lower end of spring-scale to the base, and the lateral holding-spreaders attached to the top of the fulcrum-post and projecting on each side of the front end of the balance-beam, all as hereinafter set forth.

In the accompanying drawings, the letter A designates the base or bed plate, to which is secured the fulcrum-post B, the upper end of which is slotted or bifurcated to receive the balance-beam C, which is pivoted therein at d, its arms extending in front and in rear of said post, and provided at their extremities with hooks e e'.

To the upper end of the post B are secured the lateral spreaders D, which project on each side of the front arm of the balance-bar C, and are provided at their ends with outwardly-turned holding-branches g, which are serrated or provided with catch projections or teeth h

on their outer edges, as shown in the drawings.

To the rear hook, e', of the balance-bar is attached the spring-scale E, which is also connected to the ring or staple k in the base A by an adjustable chain, l, composed of large links, so that it can be taken up or let out, as may be desired. The upper end of this chain l is provided with a snap-hook, m.

To the front hook, e, of the balance-bar is connected the arm or bow-handle of the receiver F, said handle consisting of two branches, H, which are curved outward and downward, and then inward and forward under the plate of the receiver, and are rigidly attached thereto. These arms are spread open in this manner in order that there may be no obstruction when the sack is placed with its lower end on the receiver. In this position the spreader-branches g are introduced into its mouth and serve to hold it open for the introduction of the grain, flour, or other article. As the sack is being filled the scale in rear indicates the weight.

Sometimes it may be advisable to provide a rack adjustment for the fulcrum-post, so that the balance-bar can be raised or lowered.

Having described this invention, what I claim, and desire to secure by Letters Patent, is—

The combined sack-holder and weighing device, consisting of the base A, fulcrum-post B, balance-bar C, suspended receiver F, spring-scale E, adjustable chain l, and lateral holding-spreaders D, attached to the upper end at the post, and having outwardly-turned catch-branches g, substantially as specified.

In testimony that I claim the above I have hereunto subscribed my name in presence of two witnesses.

WILLIAM THOMAS MOORE.
